DAVID E. CARPENTER, OF SPRINGFIELD, MASSACHUSETTS

INTERNAL COMBUSTION MOTOR

Application filed November 9, 1929. Serial No. 406,143.

This invention relates to internal combustion motors, and has for its main object the improvement of motors of this character in the direction of increased efficiency of operation. A further object is the improvement of motors of this character by lowering the speed at which stalling occurs and thereby increasing the range of speed in which the motor is usable. A further object is to secure 10 a greater power from the same displacement than has been possible with former constructions. These improvements are attained by a novel arrangement for completely scavenging the cylinder of exhaust gases and replacing them by a fresh charge, so that a substantially undiluted fresh charge is present at all throttle settings. The mechanism which I prefer will be described with particular reference to a usual four-cycle internal combustion 15 motor. The invention is not restricted to this use, being applicable for example to the Diesel type.

Referring to the drawings—

Fig. 1 is a sectional view of an internal 20 combustion motor embodying my invention;

Fig. 2 is a detail of a valve-timing mechanism;

Fig. 3 is a section on line 3—3 of Fig. 2;

Fig. 4 is a section on line 4—4 of Fig. 2;

30 Figs. 5, 6, 7, and 8 are diagrammatic views illustrating successive stages in the operation of the motor; and

Fig. 9 is a valve timing diagram.

The motor is shown with but a single cylinder 35 10, as the addition of other cylinders would entail mere duplication of description. This cylinder may be surrounded with the usual water-jackets 11 and has running in it a piston 12 joined by a connecting rod 13 with a crank shaft 14. Above the piston the cylinder is enlarged to provide the usual combustion space 15, which extends sideways above the inlet valve 16 and the exhaust valve 17. These valves are actuated in the customary manner from cams 18 and 19 respectively mounted on a cam shaft 20. A spark plug 21 also enters the combustion space to ignite the charge. The parts as above described are substantially standard, and have 45 therefore not been considered in detail.

According to my invention the combustion space 15 extends beyond the cylinder at the side remote from the inlet and exhaust valves so as to overlie an auxiliary chamber 22. A valve 23, shown as of the poppet type, provides an intermittent connection between the auxiliary chamber and the combustion space. The stem 24 of this valve extends downwardly through a spider guide 25 and a stuffing box 26, terminating outside the auxiliary chamber in a tappet 27. Inside the chamber the stem 24 is provided with a collar 28, between which and the spider 25 a spring 29 is compressed. The valve 23 is opened and closed twice during each cycle of the motor, 55 preferably by mechanism permitting a variance in the timing of one of its actuations. The preferred form of this mechanism will now be described.

A hollow cam shaft 30 is arranged parallel to the cam shaft 20, and is conveniently driven from the crank shaft 14 by gearing 31, 32. The cam shaft 20 is similarly driven from the crank shaft by a gear 33 meshing with the gear 31. Gears 32 and 33 are each twice 70 the size of gear 31 so that the cam shafts 20 and 30 are rotated at a common speed which is one-half the speed of the crank shaft. Within the hollow cam shaft 30 is a shaft 34 (Figs. 2, 3, and 4) through which passes 75 transversely a pin 35. This pin extends through opposite helical slots 36 in the hollow shaft 30 and preferably terminates in holes formed in a flanged collar 37 slidably mounted on the cam shaft. A ring 38 is 80 freely mounted upon the cylindrical portion of the collar, being confined between an integral flange 39 of the latter and an opposed flange 40 which may be screwed in place. The ring 38 does not rotate, but is used merely 85 for shifting the collar and the pin 35 axially along the shaft. For this purpose pins 41 are secured to the ring, fitting in yoke portions 42 of a shifting lever 43 pivoted at 90 44 to a convenient point on the machine frame. As the lever 43 is swung, the collar 38 will be moved axially of the shaft, causing the pin 35 to traverse the helical slots 36 and cause relative rotative displacement between 95 the hollow cam shaft and the inner shaft 34.

The hollow cam shaft bears a cam portion 45 positioned to contact with the tappet 27. A slot 46 is cut in the shaft 30 circumferentially in line with the cam portion 45, through which projects a cam 47 secured as by a pin 48 within a recess in the central shaft 34. The two cam portions 45 and 47 are adapted to contact successively with the tappet 27 during one cycle of the engine, the interval between their times of contact being adjustable through the mechanism which is controlled by arm 43.

The functioning of the described mechanism will now be considered with special reference to Figs. 5 to 9 inclusive. Fig. 5 shows the motor at approximately the time of ignition. The inlet and exhaust valves are of course both closed, as is the auxiliary valve 23. The piston is caused to descend by the pressure of the burning gases, and at about the bottom of the stroke the exhaust valve 17 opens as usual, remaining open during the succeeding up-stroke so that the piston drives out most of the burnt gas from the cylinder. Fig. 6 shows the piston approaching the end of the scavenging stroke. At about the point indicated the auxiliary valve 23 opens, releasing a charge of fresh gas which has been confined within the chamber 22 in a manner to be described. This fresh gas travels across the combustion space 15, forcing the residual burnt gas out the open exhaust valve port, and charging the combustion space with fresh undiluted gas. The exhaust and auxiliary valves then close.

On the succeeding downstroke of the piston, illustrated in Fig. 7, the inlet valve 16 is open and the cylinder is charged with fresh gas from the intake manifold. The inlet valve is closed, as usual, at the termination of this down-stroke. During the fourth stroke of the cycle the gas is compressed within the cylinder. It is during this latter stroke that the auxiliary valve is opened for the second time to introduce a portion of the charge into the chamber 22. The pressure in the main cylinder of course varies progressively from subatmospheric to the final compression prior to ignition. By varying the period during this stroke at which the auxiliary valve is opened, the degree of pressure serving to force the gas into the chamber 22 can be varied. Thus, without changing the length of time during which valve 23 is opened, it is possible to vary the amount of charge placed in the chamber 22. The auxiliary valve preferably closes before the piston reaches its uppermost position, so that the higher degree of compression is found only in the main cylinder.

With varying degrees of throttle opening, the amount of charge drawn into the cylinder during the suction stroke will vary. The less the charge drawn in, the less the pressure at any given period in the compression stroke.

In order to get a proper scavenging effect at the end of the exhaust stroke, it is desirable that the pressure in the auxiliary chamber be held at a uniform level irrespective of varying throttle settings. It is for this reason that I have provided the control described for the opening of the auxiliary valve during the compression. If this valve is opened, say when the pressure in the cylinder reaches atmospheric, irrespective of the particular point in the travel of the piston when this occurs, and if it is held open for a definite time in all settings, a substantially uniform charge will always be transferred to the auxiliary chamber.

The control of the variable cam 47 has been placed primarily in the lever 43. This lever is preferably controlled from the pressure in the intake manifold. To accomplish this I have shown the lever as joined by a link 50 with a bellows-type expansible and contractible member 51 of a usual construction, joined by a pipe 52 with the intake manifold. As the pressure in the latter varies, as it will with different throttle settings or engine speeds, the cam mechanism will be adjusted automatically to open the auxiliary valve at the proper time. Instead of joining the pipe 52 to the intake manifold, it can be connected to one of the auxiliary chambers 22. In this case the cam 47 will be controlled by the pressure in the auxiliary chamber rather than by the suction in the intake manifold. This is a useful modification where the variation in the engine power is controlled by changing the timing of the inlet valve instead of by a throttle, or where a supercharger is used.

What I claim is:

1. An internal combustion motor of the type having a cylinder provided with a piston and with inlet and exhaust ports, comprising a closed auxiliary chamber and means for connecting the auxiliary chamber to the cylinder once during the compression stroke of the piston to charge the chamber with fresh gas from the cylinder, and again just prior to the closure of the exhaust port whereby the fresh gas from the chamber will replace the residual burnt gas in the cylinder.

2. A four-cycle internal combustion motor of the type having a cylinder provided with a piston and with inlet and exhaust valves communicating with the combustion space above the piston at a point to one side of the cylinder, comprising a closed auxiliary chamber and means for connecting the auxiliary chamber with the combustion space at the opposite side of the cylinder from the exhaust valve, said means being operative to establish said connection once during the compression stroke to charge the auxiliary chamber with fresh gas from the cylinder, and again just prior to the closure of the exhaust valve whereby the fresh gas from the chamber

ber will replace the residual burned gas in the combustion space.

3. An internal combustion motor of the type having a cylinder provided with a piston and with inlet and exhaust ports, comprising an auxiliary chamber, means for connecting the auxiliary chamber to the cylinder once during the compression stroke of the piston to charge the chamber with fresh gas, and again just prior to the closure of the exhaust port whereby the fresh gas from the chamber will replace the residual burned gas in the cylinder, and means for controlling the portion of the compression stroke during which the said connecting means is operative.

4. A four-cycle internal combustion motor of the type having a cylinder provided with a piston and with inlet and exhaust valves communicating with the combustion space above the piston at a point to one side of the cylinder, comprising an auxiliary chamber, means for connecting the auxiliary chamber with the combustion space at the opposite side of the cylinder from the exhaust valve, said means being operative to establish said connection once during the compression stroke to charge the auxiliary chamber with fresh gas, and again just prior to the closure of the exhaust valve whereby the fresh gas from the chamber will replace the residual burned gas in the combustion space, and means for controlling the portion of the compression stroke during which the said connecting means is operative.

5. An internal combustion motor of the type having a cylinder provided with a piston and with inlet and exhaust ports, comprising an auxiliary chamber, means for connecting the auxiliary chamber to the cylinder once during the compression stroke of the piston to charge the chamber with fresh gas, and again just prior to the closure of the exhaust port whereby the fresh gas from the chamber will replace the residual burned gas in the cylinder, and means responsive to the pressure in the intake manifold for varying the portion of the compression stroke during which the said connecting means is operative.

6. A four-cycle internal combustion motor of the type having a cylinder provided with a piston and with inlet and exhaust valves communicating with the combustion space above the piston at a point to one side of the cylinder, comprising an auxiliary chamber, means for connecting the auxiliary chamber with the combustion space at the opposite side of the cylinder from the exhaust valve, said means being operative to establish said connection once during the compression stroke to charge the auxiliary chamber with fresh gas, and again just prior to the closure of the exhaust valve whereby the fresh gas from the chamber will replace the residual burned gas in the combustion space, and means responsive to the pressure in the in-

take manifold for varying the portion of the compression stroke during which the said connecting means is operative.

7. A four-cycle internal combustion motor of the type having a cylinder provided with a piston and with inlet and exhaust valves communicating with the combustion space above the piston at a point to one side of the cylinder, comprising an auxiliary chamber, means for connecting the auxiliary chamber with the combustion space at the opposite side of the cylinder from the exhaust valve, said means being operative to establish said connection once during the compression stroke to charge the auxiliary chamber with fresh gas, and again just prior to the closure of the exhaust valve whereby the fresh gas from the chamber will replace the residual burned gas in the combustion space, and means for operating said connecting means comprising a cam shaft making a complete rotation in each four strokes of the piston, a pair of cams carried by said shaft, and means for varying the angular relationship between the cams during the operation of the motor.

8. An internal combustion motor having a combustion chamber, a piston to which power is supplied by the force of the combustion of gas in said chamber and by which gas is compressed in the chamber preparatory to its combustion, and means for removing a portion of the fresh gas from the combustion chamber during the compression phase and reintroducing it into the chamber during the scavenging phase of the cycle.

9. A four-cycle internal combustion motor having a cylinder and piston defining a combustion space between them, and means for removing a portion of the fresh gas from the combustion chamber during the compression stroke of the piston and reintroducing such gas into the chamber at about the end of the scavenging stroke of the piston.

In testimony whereof I have affixed my signature.
